DESIGN FOR A COFFEE URN

Ambrose D. Olds, Wichita, Kans.

Application June 29, 1934, Serial No. 52,415

Term of patent 7 years

To all whom it may concern:

Be it known that I, AMBROSE D. OLDS, a citizen of the United States of America, residing at Wichita, in the county of Sedgwick and State of Kansas, have invented a new, original, and ornamental Design for a Coffee Urn, of which the following is the specification, reference being had to the accompanying drawing, forming a part thereof.

I claim:

The ornamental design for a coffee urn as shown.

In testimony thereof, I affix my signature.

AMBROSE D. OLDS.
